Fig. 6.

Fig. 7

FIG. 1 is a top plan view of a photographic bus embodying my new design, with the rear bumper platform in the partially extended position;

FIG. 2 is a front elevational view thereof taken from the right of FIG. 1, with the roof platform in the partially extended position;

FIG. 3 is a rear elevational view thereof taken from the left of FIG. 1, also with the roof platform in the partially extended position;

FIG. 4 is a right side elevational view thereof, in perspective, with the rear bumper platform in the retracted position and with the roof platform in the partially extended position;

FIG. 5 is a left side elevational view thereof, in perspective, also with the rear bumper platform in the retracted position and the roof platform in the partially extended position;

FIG. 6 is a right side elevational view thereof, with the rear bumper platform and the roof platform in the retracted position; and

FIG. 7 is a left side elevational view thereof, also with the rear bumper platform and the roof platform in the retracted position.

The elements shown in broken lines are included for illustrative purposes only.

I claim:

The ornamental design for a photographic bus, as shown and described.
